UNITED STATES PATENT OFFICE.

LOUIS PHILIP DESLAURIERS, OF WARE, MASSACHUSETTS.

TIRE-LINING.

1,141,697.

Specification of Letters Patent. Patented June 1, 1915.

Application filed October 28, 1914. Serial No. 868,967.

To all whom it may concern:

Be it known that I, Louis Philip DesLauriers, a citizen of the United States, and a resident of Ware, in the county of 5 Hampshire and State of Massachusetts, have made certain new and useful Improvements in Tire-Linings, of which the following is a specification.

My invention relates to tire linings especially those linings which are placed between the inner tube and outer casing of a pneumatic tire, and it consists in the combinations, constructions, and arrangements herein described and claimed.

15 An object of my invention is to provide a knitted fabric for covering inner tires, said fabric being continuous in form and being so shaped as to obviate the formation of wrinkles or creases.

20 A further object of my invention is to provide a lining of the type described in which the circular form of the tire is approximated by the woven article so that when placed in position very slight stretching will 25 bring the lining into such a position as to preclude the possibility of creases or wrinkles.

A further object of my invention is to provide a device of the type described which 30 may also be used as intermediate layers in the construction of outer casings for pneumatic tires.

Other objects and advantages will appear in the following specification and the novel 35 features of the device will be particularly pointed out in the appended claims.

My invention is illustrated in the accompanying drawings forming part of this application in which—

40 Figure 1 is a face view of a lining constructed according to my invention, Fig. 2 is a plan view of a portion of the inner side of the lining, Fig. 3 is a perspective view showing the lining applied to an inner tube,

45 Fig. 4 is a transverse section through the lining and inner tube, Fig. 5 is a section through an outer casing showing the manner in which the fabric is disposed, and Fig. 6 is a section through a modified form of the 50 device.

It is difficult to make continuous woven linings for tires due to the fact that wrinkles are apt to form when the fabric is bent into circular form. Therefore it is necessary to 55 cut woven fabric into strips, the ends of these strips overlapping.

In carrying out my invention I make use, as stated above, of a knitted fabric which is particularly well adapted for linings in that a knitted fabric can be bent without creasing where a woven fabric cannot, because of the fact that the peculiar construction of the knitted fabric will permit its stretching in one part and contracting in another, thereby obviating wrinkles and creases where the woven fabric cannot be so manipulated.

One embodiment of this invention is shown in Fig. 1. In this figure I have disclosed a knitted tube which is designed to serve as a lining for the inner tube of a pneumatic tire. In making this tube the work is started on the knitting machine with all the needles in operation with the exception of one which is taken out. The machine makes a cylindrical portion 1 having a dropped stitch along the line 2 (see Fig. 2). This is to serve as a guide for slitting the fabric to insert the inner tube of the tire.

At certain predetermined intervals a 80 gusset 3 is provided. In making this gusset all of the needles but about one-eighth at the front of the machine are thrown out of operation. Then by reciprocatory knitting the needles on each side of the gap or space 85 are gradually thrown into action until there remain only about one-eighth out of operation at the back of the machine, and again by reciprocatory knitting the same needles are gradually thrown out of operation until 90 about one-eighth remain in action at front of machine. Then all the needles are put into operation at one time. This operation produces a tapered gusset which increases the length of the fabric on one side. Now 95 when the needles are all brought into operation another cylindrical length 1 is made, then the gusset 3 is made and the operation is repeated alternately.

It will be understood that this lining is 100 knitted in long lengths which are cut into pieces suitable for the inner linings of tubes of the size desired, that is to say, for a tire to fit a wheel thirty inches in diameter the tube length would be substantially equal to the 105 circumference of the wheel; for a thirty-two inch wheel the length would, of course, be increased since the circumference of the thirty-two inch wheel would be increased. These lengths are then cut along the guide 110 line 2 and the ends of each length are looped together, thus forming a structure similar

to that shown in Fig. 1. The inner tube of the tire is now placed inside of the lining, as shown in Fig. 4, and then the lining with the inner tube are placed in the inner casing 5 or shoe of the tire.

In Fig. 1 I have shown the gussets by means of dotted lines, but it will be understood that there is really no break or interruption in the fabric at these points, the 10 stitches being continuous. Thus in Fig. 3 which shows the fabric extended there is a continuous lining which has no creases or folds.

The lining made in the manner described 15 is also well adapted for linings of straight tubes such as rubber hose, since, as stated, it can be straightened out without producing wrinkles. Such a construction is shown in Fig. 6 in which 7 denotes layers of fabric 20 and 8 layers of rubber.

In Fig. 5 I have shown another modification in which the outer casing which is constructed largely of layers of rubber 9 is provided with layers of fabric 10.

25 It will be seen that I have provided a lining of fabric which will readily adapt itself to be bent into a circular form or to be straightened out. In either case the fact that it is knitted and the further fact that the gussets are provided tend to make a lining which may be used for both purposes.

I claim:

30 1. A lining for rubber tubes comprising a knitted fabric, consisting of a plurality of cylindrical sections having their axes inclined and provided with an integral gusset at the ends of adjacent sections.

35 2. A lining for rubber tubes comprising a knitted fabric consisting of a plurality of

cylindrical sections having their axes inclined and provided with an integral gusset 40 at the ends of adjacent sections, said gusset being of substantially a wedge shape and being a continuation of the stitches of the cylindrical portions on either side thereof. 45

3. In a lining for pneumatic tires, a substantially circular continuous tube comprising a series of cylindrical sections, adjacent sections having their axes inclined toward one another and their inner edges abutting 50 one another, and gussets disposed at the ends of adjacent sections.

4. In a lining for pneumatic tires, a substantially circular continuous tube comprising a series of cylindrical sections, adjacent 55 sections having their axes inclined toward one another and their inner edges abutting one another, and wedge-shaped gussets disposed at the ends of adjacent sections, said gussets forming integral continuations of 60 the cylindrical portions on each side thereof.

5. In a lining for pneumatic tires, a substantially circular continuous tube comprising a series of cylindrical sections, adjacent 65 sections having their axes inclined toward one another and their inner edges abutting one another, and wedge-shaped gussets disposed at the ends of adjacent sections, said gussets forming integral continuations of 70 the cylindrical portions on each side thereof, the inner sides of said cylindrical portions being provided with a guide for cutting the fabric formed by omitting one of the threads.
